CLAIM

The ornamental design for a wheel for suitcase as shown and described.

DESCRIPTION

FIG. 1 is a perspective view of a wheel for suitcase showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the wheel for suitcase where the wheel for suitcase assembled to the suitcase.

The broken lines immediately adjacent to the shaded areas depict portions of the claimed design, while all other broken lines are directed to environment. The broken lines form no part of the claimed design.

1 Claim, 9 Drawing Sheets
